UNITED STATES PATENT OFFICE.

EMANUEL CHAINY, OF FLORENCE, WISCONSIN.

SAW-GUMMER.

SPECIFICATION forming part of Letters Patent No. 726,637, dated April 28, 1903.

Application filed March 12, 1902. Serial No. 97,923. (No model.)

To all whom it may concern:

Be it known that I, EMANUEL CHAINY, a citizen of the United States, residing at Florence, in the county of Florence and State of Wisconsin, have invented a new and useful Saw-Gummer, of which the following is a specification.

The present invention relates to saw-gummers or machines for deepening the interdental spaces of saws, and while particularly intended for use on crosscut-saws it will be evident that the invention may be employed upon saws of other classes.

The primary object of the invention is to provide a simple machine which may be readily placed in position upon a saw and operated to quickly cut the spaces between the teeth.

One of the important features relates to novel means for controlling the movement and action of the cutting or gumming device, whereby the operator can fully govern the same.

Other features reside in novel means for positioning and clamping the saw, said means being adjustable with relation to the gumming device, so that the position of the latter may be changed with respect to the saw held to meet the various requirements of the work.

The construction which at present is considered preferable is fully illustrated in the accompanying drawings and described in the following specification, although the invention is not to be limited to the particular construction set forth, but may be changed and modified within the scope of the appended claims.

In the drawings, Figure 1 is a view in elevation of one side of the machine. Fig. 2 is a similar view of the other side. Fig. 3 is a top plan view. Fig. 4 is a vertical longitudinal sectional view. Fig. 5 is a horizontal longitudinal sectional view. Fig. 6 is a detail perspective view of the controlling means for the gumming device. Fig. 7 is a detail perspective view of the lower end of one of the standards.

Similar numerals of reference designate corresponding parts in all the figures of the drawings.

In carrying out the invention a frame is

provided, comprising a pair of upright standards 10 and 11, connected by a web-plate 12, said web-plate having an intermediate angled offset portion 13. A pair of inwardly-extending flanges 14 are secured to the inner sides of the standards in spaced relation to the web-plate, and the flange carried by the standard 11 is provided at its upper end with an ear 15, the adjacent portion of the web being also formed into an ear 16. A bracket 17 is pivoted to and between the ears 15 and 16 and extends through a guide-opening 18, formed in the standard 10. This bracket is preferably formed of sheet metal, having downturned flanges 19 at its side edges and provided contiguous to its opposite ends with depending bearings 20. In these bearings is journaled a longitudinally-disposed arbor 21, that extends through the guide-opening 18 to the standard 10 and projects beyond the end of the bracket. This end of the bracket is preferably provided with a box 22, that extends beyond the adjacent bearing 20 and forms a covering to protect the same from the dust and cuttings. Upon the projecting end of the arbor 21 is secured by suitable nuts a grinding or gumming disk 23, which may be of any suitable material, such as emery. The opposite end of the arbor has a longitudinally-disposed key-seat 24, and a pinion 25, mounted upon this end, has a key 26, that is fitted in the seat 24. The pinion and arbor are thus held against independent rotation; but the arbor may be moved longitudinally through said pinion, which is held against the longitudinal movement by the depending bearing 20 and the adjacent ears 15 and 16. An opening 27 is made through the upper end of the standard 11 to permit the longitudinal movement of the arbor. The arbor or shaft and the gumming-disk are rotated through the medium of intermeshing gear-wheels 28 and 29, that are journaled upon the offset portion 13 of the web, one of these gear-wheels meshing with the pinion 25, the other being provided with a suitable handle-crank 30. The angular relation of the handle-crank with respect to the main frame is provided for the convenience of the operator of the machine. The bracket and gumming device are normally held in raised position by means of a spring 31, mounted upon the inner side of the web,

as shown, and having its free end 32 engaged with the under side of the bracket.

The means for controlling the action of the gumming device is as follows: A collar 33 is 5 loosely journaled upon the arbor, but is held against longitudinal movement thereon by means of sleeves 34, located at the opposite ends of the same, and said collar is provided with outstanding pintles 35, which engage in 10 openings 36, made in the lower ends of a stirrup 37, said stirrup being pivotally hung upon a pair of upstanding ears 38, attached to the upper side of the bracket. The stirrup is provided with a depending end 39, having a 15 handle 40, that is located on the side of the machine opposite to the handle-crank 30 of the driving mechanism. A centering-spring 41, coiled about the pivot 42 of the stirrup, has free terminals 43, which engage on opposite 20 sides of said stirrup and normally hold it against movement in either direction.

In order to properly position and hold the machine upon a saw, the lower ends of the standards 10 and 11 are provided with saw- 25 receiving slots 44, dividing said standards into legs 45, that are arranged to embrace the saw. Clamping devices in the form of cams 46 are journaled upon the lower ends of the standards and are movable across the slots, 30 these clamping devices being connected to an intermediately-disposed handle 47 by means of arms 48, whereby they may be moved simultaneously. It will be observed that the flanges 14 and the web 13 extend below the 35 upper ends of the saw-receiving slots, and the lower portions of these flanges and web are provided with vertically-arranged slots 49. A gage-plate 50 is located between standards and has terminal eyes 51, which receive 40 clamp-bolts 52, that pass through the slots 49. This gage-plate is therefore vertically adjustable and is intended to limit the distance the saw may be placed in the receiving-slots 44. It will also be observed that either end of the 45 gage-plate may be raised or lowered independently of the other end, so that the angular relation of the saw may be changed with respect to the gumming device.

The machine as shown is primarily intended 50 for use upon a crosscut-saw, the saw being placed in ordinary filing-clamps. The machine is then placed upon the saw, which is located in the saw-receiving slots 44, the distance being regulated by means of the gage- 55 plate 50. The clamping-cams 46 are then moved into engagement with the saw-blade, thereby securing the machine rigidly in place. The operator then standing with the gumming-disk toward him may grasp the crank- 60 handle of the driving mechanism with his right hand and the controlling-handle 40 with his left. He therefore may move the gumming-disk in three different directions. First, by revolving the driving mechanism 65 it will be evident that the disk will be rotated at a comparatively high speed. By depressing the bracket through the medium of the stir-

rup and against the resistance of the spring 31 the disk will be lowered into engagement with the saw, and in case it is not in exact 70 position by swinging the stirrup 37 back or forth the arbor, and consequently the grinding-disk carried thereby, will be moved longitudinally of the frame, so that the exact position desired may be readily obtained. As 75 soon as the pressure upon the handle 40 is released the arbor will be brought back to its normal position by the centering-spring 41, and the resistance-spring 31 will raise the bracket and the grinding-disk away from the 80 saw. The machine is then moved to the next tooth, which may be treated in like manner.

The advantages for this structure may be summed up as follows: In the first place the entire machine is comparatively simple, so 85 that it may be readily operated by one man and can be adjusted to suit the various requirements of the work. Then the machine as a whole does not have to be accurately positioned with respect to each tooth, as the operator may by means of the controlling mechanism for the gumming device adjust the same upon the frame and properly position it with respect to the space between the teeth. The means for clamping the machine upon 90 the saw is very simple and at the same time effective, while the gage-plate, as above described, permits the proper adjustment of the machine, so that the disk will be located at the necessary angle during the cutting operation. As is well known, the curve of the cutting edge of a crosscut-saw changes, and as either end of the gage-plate may be adjusted independently the machine may be adjusted 95 to conform to this curve.

From the foregoing it is thought that the construction, operation, and many advantages of the herein-described invention will be apparent to those skilled in the art without further description, and it will be understood 100 that various changes in the size, shape, proportion, and minor details of construction may be resorted to without departing from the spirit or sacrificing any of the advantages of the invention.

Having thus described my invention, what I claim as new, and desire to secure by Letters Patent, is—

1. In a saw-gumming machine, a pivoted bracket, an arbor journaled on the bracket and longitudinally movable thereon, a gumming-disk secured to the arbor, a controlling device pivoted at one end to the bracket and having an intermediate portion engaged with the arbor, and a handle secured to the free 120 end of the controlling device.

2. In a saw-gumming machine, the combination with a suitable support, of a bracket pivoted upon the support, an arbor journaled upon and movable longitudinally with respect 125 to the bracket, a gumming device secured to the arbor, and a stirrup pivotally hung upon the bracket and connected to the arbor.

3. In a saw-gumming machine, the combi-

nation with a support, of a bracket pivoted thereto, an arbor journaled upon the under side of the bracket and longitudinally movable thereon, a collar mounted upon said arbor, a gumming-disk secured to the arbor, and a controlling device pivoted to the bracket and engaging said collar.

4. In a saw-gumming machine, a frame comprising spaced upright standards and a web-plate connecting the standards, of a bracket pivoted to the frame, an arbor journaled upon the bracket and longitudinally movable thereon, a gumming device carried by the arbor, a pinion mounted against rotatable movement on the arbor but permitting the longitudinal movement of the same, and gearing journaled upon the web-plate and meshing with said pinion.

5. In a saw-gumming machine, the combination with a suitable support, of a bracket pivoted to the support, an arbor journaled upon and movable longitudinally with respect to the bracket, a gumming device secured to the arbor, and manually-operated mechanism for moving the bracket and also moving the arbor longitudinally thereof, said means having separate engagements with the arbor and the bracket, the engagement with the bracket serving to hold the bracket against rotation with the arbor.

6. In a saw-gumming machine, the combination with a suitable support, of a bracket pivoted upon the support, an arbor journaled upon and movable longitudinally with respect to the bracket, a gumming device secured to the arbor, and controlling means for the gumming device connected to the arbor, and movably attached to the bracket, being held by such attachment against rotation with the arbor.

7. In a saw-gumming machine, the combination with a suitable support, of a bracket pivoted upon the support, an arbor journaled upon and movable longitudinally with respect to the bracket, a gumming device secured to the arbor, and controlling means for the gumming device connected to the arbor, and pivoted to the bracket, being held by its pivot connection against rotation with the arbor.

50 8. In a saw-gumming machine, the combination with a suitable support, of a bracket pivoted upon the support, an arbor journaled upon and movable longitudinally in either direction with respect to the bracket, a gumming device secured to the arbor, operating mechanism for moving the bracket and the arbor longitudinally upon the same, and yielding means for normally holding the arbor at an intermediate point against longitudinal movement in either direction.

9. In a saw-gumming machine, the combination with a suitable support, of a bracket pivoted upon the support, an arbor journaled upon and movable longitudinally with respect to the bracket, a gumming device secured to the arbor, a stirrup pivotally hung upon the bracket and connected to the arbor, and a

centering-spring engaging the stirrup to normally hold it against movement.

10. In a saw-gumming machine, the combination with a frame or extension that is provided with a guide-opening, of a bracket pivoted upon the frame and projecting through the opening, the lower end wall of said opening constituting a stop to limit the swinging movement of the bracket, an arbor journaled upon the bracket and projecting beyond the free end thereof, a gumming device carried by the projecting end of the arbor, driving mechanism mounted upon the frame and connected with the arbor, and a gage arranged to rest upon the saw-teeth and adjustably secured to the frame and movable toward and from the stop formed by the end wall of the opening.

11. In a saw-gumming machine, the combination with a frame provided with a guide-opening having a wall that constitutes a stop, of a bracket pivoted upon the frame and projecting through the guide-opening, being arranged to contact with the stop-wall thereof, an arbor journaled upon the bracket and projecting through the guide-opening of the standard, a gumming device carried by the end of the arbor that projects through the guide-opening, means for driving the arbor, and a spring mounted upon the frame on the side of the bracket opposite the gumming device and engaging the bracket to normally hold the same against the stop-wall of the guide-opening.

12. In a saw-gumming machine, the combination with a frame arranged to be placed upon a saw, of a gumming device mounted upon the frame, and a substantially horizontal gage-plate adjustably secured to the frame and vertically movable thereon, said plate being arranged to rest upon the upper edge of the saw and being movable toward and from the gumming device.

13. In a saw-gumming machine, the combination with a frame having depending standards provided with saw-receiving slots, of a gumming device movably mounted upon the frame, and a substantially horizontal gage-plate located between the standards and movable vertically thereon said plate being arranged to rest upon the saw-teeth and limit the distance the saw may be placed in the slots.

14. In a saw-gumming machine, the combination with a frame having depending standards provided with saw-receiving slots, of a gumming device movably mounted upon the frame, flanges located upon the inner sides of the standards and having longitudinally-disposed slots, a gage-plate located between the standards and movable toward and from the gumming device, and adjusting-bolts secured to the ends of the gage-plate and movably mounted in the slots of the flanges.

15. In a saw-gumming machine, the combination with a frame having spaced standards provided with saw-receiving slots, of a gum-

ming device movably mounted on the frame, clamping devices secured to the standards and movable across the slots thereof to clamp a saw placed in said slots, and a connection 5 between the several clamping devices whereby they are movable simultaneously.

16. In a saw-gumming machine, the combination with a frame having spaced standards provided with saw-receiving slots, of a gumming device movably mounted on the frame, clamping-cams journaled upon the standards and movable across the slots thereof, and a handle located between the standards and having connections with the cams to move 15 them simultaneously.

17. In a saw-gumming machine, the combination with spaced standards having saw-receiving slots in their lower ends and guide-openings in their upper ends, of a web-plate 20 connecting the standards, a bracket pivoted upon the web-plate and projecting through one of the guide-openings, the ends of which constitute stops to limit the movement of the

bracket, an arbor journaled upon the bracket and projecting through one of the guide-openings, said arbor being longitudinally movable upon the bracket, a grinding-disk attached to the projecting end of the arbor, gearing mounted upon the web-plate and having a gear connection with the arbor, clamping-cams journaled upon the lower ends of the standards and movable across the saw-receiving slots, and a vertically-adjustable and horizontally-disposed gage-plate mounted upon the web-plate and movable toward and 35 from the bracket, said gage-plate being located in a plane that intersects the saw-receiving slots.

In testimony that I claim the foregoing as my own I have hereto affixed my signature in the presence of two witnesses.

EMANUEL CHAINY.
